UNITED STATES PATENT OFFICE.

ADA MARIAN ELLIS, OF OAKLAND, CALIFORNIA.

READING STAND.

Application filed May 10, 1926. Serial No. 107,985.

My invention relates to improvements in collapsible book-holding stands, and it consists in the combinations, constructions, and arrangements, hereinafter described and 5 claimed.

An object of my invention is to provide a collapsible book-holding stand which is especially designed to be secured to a bed for holding a book in a position to permit the 10 book to be read by a person lying in bed.

A further object of my invention is to provide a device of the type described in which a stand is constructed in a novel manner for permitting the stand to be adjustably 15 secured to a bed, the supporting legs of the stand being collapsible into a tubular shape and being slidably into the main body of the stand.

A further object of my invention is to provide a device of the type described in which 20 all of the parts are collapsible into a small unit, thus permitting the device to be readily shipped from place to place at a slight expense.

25 Other objects and advantages will appear in the following specification, and the novel features of the invention will be more particularly pointed out in the appended claims.

My invention is illustrated in the accompanying drawings, in which Figure 1 is a front elevation of the device,

Figure 2 is a section along the line 2—2 of Figure 1, and

Figure 3 is a section along the line 3—3 of 35 Figure 1.

In carrying out my invention I provide a tubular support consisting of a tube 1, and a tube 2 slidably received in the tube 1 and being adjustably secured thereto by a wing 40 screw 3.

The support 1 is held in vertical position by three semi-cylindrical collapsible legs 4, 5, and 6. The legs 4 and 5 are hingedly secured to the tube 2 at 7 and 8 and are adapted 45 to be swung down into the dotted line position shown in Figure 2. Figure 1 shows how the leg 6 is hinged to the tube 2 at 9 and is adapted to swing in a plane at right angles to the swinging of the legs 4 and 5.

50 The legs 4 and 5 lock against the tube 2 so as to prevent the rocking of the tube about the leg 6 as a pivot. The leg 6 has a tapered end 10 engaging with a projection 11, see Figure 2, which prevents the support 1 from swinging down upon the leg 6. A spring-pressed catch 12 engages with a pin 13 car-

ried by the leg 6 and prevents the support 1 from swinging to the right in Figure 1. It will be seen from this construction that the support 1 is sufficiently braced to carry the 60 book support hereinafter described.

The support 1 is adjustably secured to a bed frame 14, whereby the device is held in a fixed position with respect to the bed. The means for securing the stand to the bed comprises a tubular upright 15 hingedly secured at 16 to the leg 6. A plunger 17 carrying a 65 vacuum cup 18 is slidably received in the upright 15 and is held in adjusted position by means of a wing screw 19.

The book stand 20 is of the collapsible type and a casing 21 carrying lights 22 is detachably secured to the book stand 20. Bars 23 are pivotally secured to the stand 20 at 24, see Figures 1 and 3, and have their 70 free ends receivable behind the casing 21. The bars 23 hold the book, not shown, in place upon the book stand.

In Figure 3 I show how the book stand 20 is adjustably and pivotally secured to a standard 25 at 26. The standard in turn is carried by the free end of a lazy tong 26', the other end of the lazy tong being secured to the tube 1.

From the foregoing description of the various parts of the device the operation thereof may be readily understood. In Figure 1 I show a section of a frame 14 of a bed together with a section 27 of the spring frame. In this figure all of the parts making up the 90 device are shown in operative position. The support 1 is lengthened to the height desired, the lazy tong 26' is extended to the desired position, the plunger 17 is raised so as to cause the vacuum cup 18 to contact with the frame 14, and the book stand 20 is rigidly secured in place by means of the wing clamp 26. The book in the book stand will now be 95 held in a position to permit a person lying in bed to read the same. The pages of the book may be turned one at a time and disposed behind the bars 23 after being turned.

In collapsing the device, the casing 21 is removed from the book stand 20, and then the book stand together with the lazy tong 10: 26' is collapsed and will assume a position adjacent to the tube 1. The plunger 17 may now be moved into the upright 15 and be locked in place by the wing screw 19. The catch 12 is now manually released, thus permitting the 110 leg 6 to be swung into the dotted line position shown in Figure 1. The leg is semi-cylindri-

cal in shape and therefore receives the upright 15 together with the plunger 17. The legs 4 and 5 may now be swung into the dotted line position shown at Figure 2 and will enclose 5 a portion of the leg 6 and the upright 15. The legs 4 and 5 when in closed position have an outer diameter of the same size as the outer diameter of the tube 2. The tube 1 is of a sufficient length to permit the tube 2 together 10 with the legs 4, 5, and 6 and the upright 15 to be moved into the tube and locked in position by the wing screw 3. The device now occupies a very small space, and may be readily shipped from place to place at a slight expense. The device is extremely simple in 15 construction and provides a rigid book carrying stand which is readily adjustable for holding the book in any position desired.

I claim:

- 20 1. A device of the type described comprising an extensible support, collapsible legs for holding said support in operative position, said legs being movable into said support, a collapsible book-holder, collapsible means for supporting said book-holder at different positions from said support, and means for adjustably securing said device to a bed, means on said support for bracing it on the floor.
2. A device of the type described comprising an extensible support, collapsible legs for holding said support in operative position, said legs being movable into said support, a collapsible book-holder, collapsible means for supporting said book-holder at different positions from said support, and means for adjustably securing said device to a bed, said last named means being collapsible into said support.

3. In a device of the type described, an outer tube, an inner tube slidable into and out of said outer tube, means for locking said inner tube in adjusted position to said outer tube, semi-cylindrical legs hingedly carried by said inner tube and being swingable from operative position into closed position, whereby said legs are receivable in said outer tube, and another leg hingedly secured to said inner tube and extending at an angle to said first named legs when said legs are in operative position, and means for rigidly securing said last named leg to said inner tube.

4. In a device of the type described, an outer tube, an inner tube slidable into and out of said outer tube, means for locking said inner tube in adjusted position to said outer tube,

semi-cylindrical legs hingedly carried by said inner tube and being swingable from operative position into closed position, whereby said legs are receivable in said outer tube, another leg hingedly secured to said inner tube and extending at an angle to said first named legs when said legs are in operative position, and means for rigidly securing said last named leg to said inner tube, and an adjustable upright carried by said last named leg for abutting a bed frame, said upright being receivable in said outer tube.

5. In a device of the type described, an outer tube, an inner tube slidable into and out of said outer tube, means for locking said inner tube in adjusted position to said outer tube, semi-cylindrical legs hingedly carried by said inner tube and being swingable from operative position into closed position, whereby said legs are receivable in said outer tube, another leg hingedly secured to said inner tube and extending at an angle to said first named legs when said legs are in operative position, and means for rigidly securing said last named leg to said inner tube, and an adjustable upright carried by said last named leg for abutting a bed frame, said upright being receivable in said outer tube, said adjustable upright comprising a tubular member hingedly secured to said last named leg, a plunger slidably mounted in said member, means for securing said plunger in adjusted position, and a vacuum cup carried by said plunger.

6. In a device of the type described, an outer tube, an inner tube, semi-cylindrical legs carried by said inner tube and providing an extension for said inner tube when said legs are in folded position, and a third leg secured to said inner tube being receivable in said first named legs when said legs are folded.

7. In a device of the type described, an outer tube, an inner tube, semi-cylindrical legs carried by said inner tube and providing an extension for said inner tube when said legs are in folded position, and a third leg secured to said inner tube being receivable in said first named legs when said legs are folded, and an adjustable bracing member carried by said third named leg and being partially received therein when said bracing member is in folded position.

In testimony whereof I affix my signature.

ADA MARIAN ELLIS.
